UNITED STATES PATENT OFFICE

ANDREW T. HAYASHI, OF VENTNOR, NEW JERSEY, AND WILLIAM C. HYZER, OF PITTSBURGH, PENNSYLVANIA; SAID HYZER ASSIGNOR TO SAID HAYASHI

DESIGN FOR AN ELECTRICALLY-OPERATED GAME

Application filed May 7, 1930. Serial No. 35,532. Term of patent 14 years.

To all whom it may concern:

Be it known that we, ANDREW T. HAYASHI, a subject of the Emperor of Japan, residing at Ventnor, in the county of Atlantic in the State of New Jersey, and WILLIAM C. HYZER, a citizen of the United States, residing at Pittsburgh (West View Park), in the county of Allegheny and State of Pennsylvania, have invented a new, original, and ornamental Design for Electrically-Operated Games, of which the following is a specification, ref-

erence being had to the accompanying drawing, forming part thereof, in which:

Fig. 1 is a front perspective view of our new design;

Fig. 2 is a side elevation of the same.

We claim:

The ornamental design for an electrically operated game, as shown.

ANDREW T. HAYASHI.
WILLIAM C. HYZER.
